ISIDORE PANES, OF NEW YORK, N. Y.

CORSET

Application filed January 2, 1930. Serial No. 418,074.

This invention relates to corsets, and has for an object to provide an improved construction wherein a desired system of lacing may be had at the back with disengageable fastening means at the front, the lacing at the back being associated with covering means resiliently held in place.

Another object of the invention is to provide a corset of the back laced type with a covering flap and adjustable, elastic tabs for holding the lower part of the covering flap in place.

A further object, more specifically, is to provide in a corset elastic portions at the back with lacings from the elastic portions to the bottom, whereby adjustments may be had for the full length of the corset, the arrangement being such that the lacings are normally covered and the covering means resiliently held in place at the lower end and permanently held in place at the upper end.

In the accompanying drawings,—

Figure 1 is a rear view of the corset disclosing an embodiment of the invention, the corset being shown spread;

Figure 2 is a rear view of the central part of the corset shown in Figure 1, the same illustrating the elastic members in a distended or stretched condition;

Figure 3 is a sectional view through Figure 2 on the line 3—3, the same being on an enlarged scale.

Referring to the accompanying drawings by numerals, the corset is provided with a body which comprises a back structure 1 and a front structure 2. These structures may be formed in substantially any desired way, except that the back structure 1 has certain, special features, as illustrated particularly in Figures 1 and 2. The back 1 is formed with panels 3 and 4, and connected to these panels at their upper ends are elastic pieces 5 and 6. Below the elastic pieces 5 and 6 are connected pieces or sections 7 and 8 which merge into an upper section 9 connected to the upper part 10 of the covering flap 11. The covering flap 11 and section 9 are secured by lines of stitching 12 and 13 to the edges of members 5 and 6. By this construction and arrangement the flap of cover-

ing member 11 is held centrally, while the upper part of the body of the corset may be distended, by reason of the elasticity of members 5 and 6. The center and lower part of the corset may be distended, by reason of the fact that members or sections 7 and 8 are connected by lacing 14. It will be understood that this lacing may be caused to pull the edges of sections 7 and 8 toward each other, or release these sections so as to provide a larger opening. So far as adjusting the size of the corset is concerned, the flap 11 would not be necessary as the lacings 14 take care of this adjustment. However, lacings, even at the rear of a corset, are objectionable in many cases, as they may be seen through thin dresses and also present objectionable protrusions. To obviate these objections, the covering member or flap 11 is provided, said covering member or flap 11 extending down to adjacent the lower edge of the corset body. As illustrated in Figures 1 and 2, this flap flares at the bottom part because usually the opening between sections 7 and 8 normally flares. In order to keep the flap centrally positioned over the lacings 14, while allowing the flap to yield, elastic members 15 and 16 are provided, said members being stitched or otherwise rigidly secured to the sections 3 and 4 at one end, while at the opposite end they are provided with hooks 17 and 18. These hooks are adapted to interlock with the respective eyelets 19, 20, 21 and 22. When the opening between sections 7 and 8 is small, the hooks 17 and 18 are interlocked with the eyelets 20 and 21, whereas if the opening is great, as shown in Figure 2, the hooks are interlocked with eyelets 19 and 22. From Figure 2 it will be observed that the upper part or section 10 of flap 11 is stretched to its fullest extent, while the elastic members 5 and 6 are stretched somewhat, and also the members 15 and 16 are stretched somewhat. Regardless of the adjustment of the lacings 14 the members 15 and 16 will act to resiliently hold the lower part of the flap centrally positioned in respect to the lacings 14.

What I claim is:—

1. A back laced corset formed with a body

open at the back, a flap loosely fitting over said opening, a pair of elastic panels connecting the upper part of said flaps to the body near the upper part thereof, and a pair of elastic members acting on each side of the flap near the bottom for maintaining the flap centered over said opening.

2. A back laced corset formed with the body open at the back from top to bottom, a panel extending from each edge of said opening, said panels extending from the bottom to a point below the top of said body, a flap loosely fitting over said opening and extending from the top to the bottom of said body, an elastic fabric section on each side of said flap at its upper end, said elastic members extending from the upper edge of the corset downwardly to a point below the top of said panels, lacings for regulating the size of said opening, and resilient means at the lower end of said flap for holding the flap over said opening and said lacings.

3. A corset comprising a body provided at the front with disengageable fastening means, a panel structure at the back, said panel structure including a pair of strips of non-elastic fabric extending from the bottom of the body to near the top thereof, each of said strips being connected along one edge to said body, lacing for drawing the other edges of said strips toward each other, a covering strip wider at the bottom than at the top and extending from the top to the bottom of said body positioned to cover said lacing, said covering strip being narrower than the combined width of said pair of strips, a panel of elastic fabric at each side of the upper part of said covering strip extending from the top of said body to a point below the top of said pair of strips, said elastic panels being connected respectively to said covering and to said body, and a pair of disengageable elastic members for holding the lower part of said covering strip centrally of said pair of strips.
